UNITED STATES PATENT OFFICE

HOWARD C. MASSEY, OF KANSAS CITY, MISSOURI

BACON FORMING OR SHAPING MACHINE

Application filed April 23, 1929. Serial No. 357,489.

The present invention relates to improvements in bacon-forming or shaping machines, the primary object of the invention being the provision of a machine wherein a slab of bacon may be compressed both from above and at the sides thereof to shape the same into uniform slabs solely by compressive action, thus eliminating cutting or trimming of the slab.

10 Another object of this invention is the provision of a novel form of mold in which mechanism is provided for compressing the sides thereof upon the bacon therein while a superimposed roller engages the upper surface of the bacon to compress the same within the mold, thereby providing means to accommodate bacon slabs of various widths and thicknesses and to mold the same into uniform and attractive shape.

20 Still another object of the present invention is the provision of means for preventing any slip between the main roller and bacon during the rolling of the roller over the bacon.

25 With the foregoing and other objects in view, which will appear as the description proceeds, the invention resides in the combination and arrangements of parts and in the details of construction hereinafter described and claimed, it being understood that changes 30 in the precise embodiment of the invention herein disclosed can be made within the scope of what is claimed without departing from the spirit of the invention.

35 In the accompanying drawings:—

Figure 1 is a side elevation of the complete machine;

Figure 2 is an end view thereof taken from the right, as viewed in Figure 1, and on an enlarged scale with legs removed;

40 Figure 3 is a top plan view of the mold with the side walls in their normal extended position;

Figure 4 is a section taken on line 4—4 of Figure 3;

45 Figure 5 is a section taken on line 5—5 of Figure 3;

Figure 6 is a side view of one of the mold supporting members;

50 Figure 7 is an end view thereof;

Figure 8 is a section taken on line 8—8 of Figure 3;

Figure 9 is a section taken on line 9—9 of Figure 1;

55 Figure 10 is an enlarged detail side elevation of the operating lever whereby reciprocating motion is imparted to the main roller carrying yoke.

60 Referring to the drawings, numeral 11 designates the supporting legs of the machine, the cross-pieces 12 support two I-beams 13 and 14 disposed longitudinally and parallel to each other for supporting the operated as well as the operating mechanisms of the machine.

65 Carried by the two beams 13 and 14, and upstanding from the inner flanges thereof, are four fixed pins 15, the purpose of which will presently appear. Mounted upon the upper surface of the beams 13 and 14 are two plates 16 and 17, each constructed identically but disposed in opposite positions so as to be moved to and from each other, their wedges 18 being disposed to form an adjusting mechanism to raise and lower a mold plate or bed 24. A rod 20 threadably engages the plate 16—17 at 21 and 22, and as the threads of this rod 20 are, respectively, right- and left-hand threads, a shouldered portion 23 thereof, when rotated by a handle H, will cause the wedges 18 to be moved toward or away from each other, and inasmuch as the rod 20 is disposed between two apertured projections 26 with a fixed cylinder 27 carried by said rod mounted therebetween, the rod itself does not move longitudinally when rotated but causes the movement of said wedges. These wedges 18 coat with the inclined portions 25 of the mold bed plate or base 24 and the latter is moved upwardly or downwardly upon the pins 15 by the consequent rotation of the rod 20.

70 Carried at the forward end of the mold bed plate 24 are two apertured and spaced lugs 29 which receive, respectively, pivoting pins or screws 30 to secure the forward ends 28 of the respective side molding members or walls 31 so that the same may be moved to assume the full and dotted line positions as 75

80 85 90 95 100

shown in Figure 3, the inner surfaces being adapted to engage the side of bacon while resting upon the base plate 24 so as to shape and confine the sides thereof.

- 5 Formed in the free end, at the under side of each of the walls 31, is a recess 32 in which a stud 33 fits, this stud being attached to and movable with a sleeve 34 which, as clearly illustrated, slides upon a guide rod 35 mounted in a recess 36 of the plate 24 at the forward edge thereof. There are, therefore, two of these sleeves 34 mounted upon the rod 35, while a spring 37 is disposed upon the rod between the sleeves and has a tension outwardly 10 so as to separate the sleeves. Thus, when the walls 31 are free to move, and the spring causes them to assume the position as clearly illustrated in Figure 3.

In order to impart movement to said walls 31 in opposition to the spring 37, the outer edges 38 are flanged to receive rollers 39, there being one to each wall. These rollers are connected to and supported from respective projections 40 of a frame 41, and this frame 41, 25 as clearly illustrated in Figure 1, is provided with a stud 42 in the lower end carrying a roller 43 which engages, respectively, the base flange at the outer portion of each of the beams 13 and 14 and these, when desired, 30 carry the full weight of the main roller 45 mounted for rotation upon a shaft 44 in a main yoke 41', of which yoke the arms 41 constitute a part.

In order that the desired reciprocating movement may be imparted to the yoke 41' and, consequently, the main roller caused to be rotated above the mold, and the walls 31 to be moved toward each other as the main roller is operated in one direction or to the 40 right, as illustrated in Figure 1, a rod 50 is connected to the yoke 41' and is guided in bearings 51 and 52 mounted in the respective supports 49 and 53. A coupling 54 is connected to the rod 50 between the bearings 51 and 52 and is pivotally connected at 55 to a short link 56 which, in turn, is pivotally connected at 57 to the upper end of an operating lever 57'. This lever 57' is mounted upon a shaft 60 supported in a frame 61 depending 50 from the beams 13 and 14 and supported thereby. A pin and roller 62 is mounted for sliding movement in a slot 63 of the lever 57 and, through a link 64 and its stud shaft 65, connects the same to gearing 66 so that said 55 lever 57' will have the desired reciprocating movement imparted thereto and, in turn, impart straight-line reciprocation to the rod 50.

Connected to operate the gear mechanism is a prime mover, here shown as an electric motor 67, which drives a sprocket wheel 69 through a silent chain 68.

Thus, it will be apparent that when the motor is operated the main roller 45 will be reciprocated and will ride upon the side of bacon exposed within the mold and the roll-

ers 39 will cooperate with said pivoted walls 31 thereof to move the same inwardly against the action of the spring 37 to compress the sides simultaneously with the downward pressure upon the upper face or surface of the bacon due to the action of the main roller 45, thus forming the side or slab of bacon in a compact parallel mass of uniform thickness and width.

The walls 31 may be of varying heights and may also be wider or narrower than here shown to the end that they may be interchanged for action upon bacon slabs of various sizes. By manipulating the rod 20, the entire mold may be raised or lowered to receive the desired compressing action of the roller 45 in accordance with the thickness of the bacon slabs to be operated upon.

In order that the main roller may be prevented from slipping during the rotation thereof when reciprocated over the side of the bacon slab, the two supports 48 and 49 carry a toothed rack bar 47 at one side of the machine above the beam 13. Mounted thereupon for rotation with the main roller 45 is a gear 46 which meshes at all times with the teeth of the bar 47. Thus, as the rod 50 is reciprocated and moves the roller 45 to and from the end of the machine, as illustrated in Figure 1, the teeth of the rack bar 47 and the gear 46 cooperate to insure an even rotation of the main roller and thereby, as above stated, prevent the surface of the roller from slipping upon the surface of the bacon slab.

The operation of the machine will, from the foregoing description considered in conjunction with the drawings, be readily understood, but, briefly stated, it is as follows:—

The mold is adjusted vertically by manipulation of the handle H so that the upper surfaces of the walls 31 are disposed in a plane for engagement by the roller 45. The roller 45 is then in the position as shown in dotted lines in Figure 1 and the walls 31 are in the full line position as shown in Figure 3. The side or slab of bacon is then placed upon the bed plate 24 between the walls 31 and the prime mover is initially operated so that the rod 50 moves the roller from left to right, as shown in Figure 1. Simultaneously with the engagement of the roller 45 with the upper surface of the slab of bacon, the rollers 39 engage the flanges 38 of the walls 31 and move them inwardly against the tension of the spring 37. Thus pressure is exerted upon the slab of bacon simultaneously from above and at the sides thereof, the movement of the roller from right to left, as shown in Figure 1, completing the compressing operation and causing the rollers 39 to free the walls 31 to the action of the spring 37, which thereby causes the free ends of the walls to move to the full line position, as shown in Figure 3, and to free the formed or shaped slab of bacon for removal from the mold.

What I claim is:—

1. A bacon-forming machine including a frame, a main roller reciprocatingly mounted therein, and a bacon mold mounted upon the frame and disposed to hold the bacon with the top exposed to the roller to permit the roller to compress the bacon into the mold.

10 2. A bacon-forming machine including a frame, a main roller reciprocatingly mounted therein and an adjustable bacon mold mounted upon the frame and disposed to hold the bacon with the top exposed to the main roller to permit said roller to compress the bacon into the mold.

15 3. A bacon-forming machine including a frame, a main roller reciprocatingly mounted therein, and an adjustable bacon mold mounted upon the frame and disposed to hold the bacon with the top exposed to the main roller to permit said roller to compress the bacon into the mold, said mold having a fixed base and two spring projected side walls, and means operable with the roller for simultaneously moving the walls toward each other as the 20 main roller is moved over the mold in one direction.

4. A bacon-forming machine including a frame, a main roller reciprocatingly mounted therein and an adjustable bacon mold mounted upon the frame and disposed to hold the bacon with the top exposed to the main roller to permit said roller to compress the bacon into the mold, said mold having a fixed base and two spring projected side walls, and means operable with the roller for simultaneously moving the walls toward each other as the main 30 roller is moved over the mold in one direction, said side walls being released as the roller is moved in the opposite direction due to the action of the spring tension thereon to permit free access to the formed bacon.

35 5. A bacon-forming machine according to claim 3, in which the means for simultaneously moving the walls toward each other includes two rollers engaging from opposite directions said walls and movable with the main roller, said two rollers being arranged to compress the walls against the spring tension when the main roller is moved in one direction and to free the walls to the spring action when the main roller is moved in the opposite direction.

45 6. A bacon-forming machine according to claim 4, wherein the side walls are pivotally mounted at their forward ends to the fixed base of the mold, and an extension spring bearing against the walls to space the free ends thereof.

50 7. A bacon-forming machine according to claim 2, wherein manually operable adjusting means is provided to bodily elevate and lower the mold.

55 8. A bacon-forming machine according to claim 2, wherein two wedges support the mold upon the frame, and a right- and left-hand screw member is provided to move the

wedges toward and from each other to thereby cause the mold to be bodily raised or lowered.

9. A bacon-forming machine according to claim 1, wherein means is provided for insuring the positive rotation of the main roller as the same is reciprocated.

10 10. A bacon-forming machine according to claim 1, wherein a fixed toothed rack is mounted upon the frame adjacent the main roller, and a gear rotatable with the main roller and meshing with the rack to insure positive rotation of the main roller during the reciprocation of the main roller.

15 11. A bacon-forming machine according to claim 1, wherein means to reciprocate the main roller is provided which includes a yoke connected to the main roller, a rod connected to the yoke and mounted in the frame, a prime mover, and a lever operably connected to the prime mover and to the rod and reciprocated by the prime mover to impart reciprocation to the rod.

20 In testimony whereof I have hereunto set my hand.

HOWARD C. MASSEY.
